DESIGN FOR A MEAT HOLDER

Eugene S. Morfesi, Flushing, N. Y.

Application January 11, 1947, Serial No. 136,107

Term of patent 7 years

(Cl. D44—29)

To all whom it may concern:

Be it known that I, Eugene S. Morfesi, a citizen of the United States, residing in Flushing, in the county of Queens, Long Island, and State of New York, have invented a new, original, and ornamental Design for a Meat Holder, of which the following is a specification, reference being had to the accompanying drawing. The drawing is constituted as follows:

Fig. 1 is a side view of a meat holder, showing my new design;

Fig. 2 is a top plan view; and

Fig. 3 is an end view thereof.

I claim:

The ornamental design for a meat holder, as shown.

EUGENE S. MORFESI.
